UNITED STATES PATENT OFFICE.

ERNEST HAMILTON HEINKE, OF LONDON, ENGLAND.

BOAT-PROPELLING MECHANISM.

1,120,485.

Specification of Letters Patent.

Patented Dec. 8, 1914.

Application filed June 30, 1913. Serial No. 776,622.

To all whom it may concern:

Be it known that I, ERNEST HAMILTON HEINKE, a citizen of the United Kingdom of Great Britain and Ireland, and resident of 54 South Molton street, London, England, have invented certain new and useful Improvements in Boat-Propelling Mechanism, of which the following is a specification, such as will enable others skilled in the art to which it appertains to make and use the same.

This invention relates to motors and propellers for attachment to boats and other floating bodies and refers to that type of machine in which an internal combustion engine or other motor arranged above the water line is adapted to drive a vertical shaft, the lower end of which is in gear with a propeller below the water line.

The invention concerns particularly a better arrangement for mounting the appliance upon the boat or other floating body whereby it can be entirely raised from the water and placed upon the deck or equivalent of the boat.

The invention also includes details of construction relating particularly to the arrangement for steering, the brackets employed for mounting the motor and other features hereinafter described and claimed.

In the accompanying drawings, Figure 1 shows a form of the invention designed to be clamped to the stern of the boat and to be supported thereon by a V-shaped bracket. Fig. 2 shows a detail of the steering gear. Fig. 3 shows an appliance of slightly modified construction and illustrates how the same can be swung over on to the deck of the boat. Fig. 4 illustrates a further modification particularly concerning the brackets employed. Fig. 5 is a side elevation of the bracket for supporting the motor in operative position, and Fig. 6 is a plan of the same when in the position of Fig. 5.

Referring to Fig. 1, the motor T is attached by means of bracket R and screw W to the stern or transom N of the boat. The motor drives pinion Q which is in mesh with pinion P on the vertical shaft B, the said shaft being inclosed in the hollow shaft E and having at its lower end the pinion J in mesh with pinion K on shaft L to which the propeller is fixed. Pinions J and K are contained in the gear case A which has an extension C in line with the hollow shaft E

and is adapted to be turned by means of a cog wheel F which is keyed to the extension C and is in mesh with the wheel G on the shaft S, the said shaft being adapted to be turned by any suitable means such as a flexible shaft to which it may be connected.

It will be seen from Fig. 2 that the wheel F is keyed to the sleeve or extension C and it will be obvious that if the wheel G is turned by shaft S it will rotate wheel F and thereby swing the propeller around and thus enable the boat to be steered, or driven astern.

The wheels F and G are inclosed in the case H to which the V-shaped or angle bracket N is pivotally fitted, the said bracket being composed of two symmetrically disposed members each consisting of an inner part pivoted at its inner end to the pivot U and resting, when in operative position, with its lower part on the stop V on the stern of the boat. When the appliance is moved from operative to inoperative position, the whole appliance is swung over onto the deck, the bracket M pivoting on the pivot U.

In Fig. 3 the steering and reversing gear is arranged close to the motor and the drawing clearly shows how the appliance can rest on the deck Z of the boat.

In Fig. 4 links R² pivoted at R³ to the motor and at R⁴ to brackets on the deck Z are used in place of the bracket and screw R, W, shown in Fig. 1.

It will be observed that the peculiar formation of the bracket M permits the appliance being turned well over on to the deck and also that the shape of the bracket allows the propeller to be swung completely around and placed under the bracket for driving astern in addition to which the forward drive of the propeller is conveyed in very direct manner to the boat.

Obviously instead of placing the appliance on the deck it can be received upon any suitable support.

What I claim and desire to secure by Letters Patent is:—

1. In a boat propelling mechanism, the combination of a motor; a propeller operatively connected thereto; a link pivotally connecting the propeller to the boat; and a link pivotally connecting the motor to the boat.

2. In a boat propelling mechanism, the

combination of a motor; a propeller operatively connected thereto; and a pair of links, one above the other, pivotally connecting the motor and propeller to the boat.

5. 3. An appliance for use with boats comprising an outboard motor and a propeller, a pair of pivoted links supporting the motor and a pivoted bracket of substantially double V shape supporting the propeller, a shaft between the motor and the propeller, a toothed gear on the motor, a toothed gear on the propeller, a toothed gear on the upper end of the shaft co-acting with the toothed gear on the motor, a toothed gear on the lower end of the shaft co-acting with the toothed gear on the propeller, and means whereby the propeller can be rotated around the axis of the shaft.

4. An appliance for use with boats comprising an outboard motor and a propeller, a pair of pivoted links supporting the motor and a pivoted bracket of substantially double V shape supporting the propeller, said bracket extending from its supporting point 25 of the propeller to stops fixed to the boat and upwardly therefrom to the pivots whereby it is connected to the boat, a shaft between the motor and the propeller, a toothed gear on the motor, a toothed gear on the propeller, a toothed gear on the upper end of the shaft co-acting with the toothed gear on the motor, a toothed gear on the lower end of the shaft co-acting with the toothed gear on the propeller, and means

whereby the propeller can be rotated around the axis of the shaft.

5. An appliance for use with boats comprising an outboard motor and a propeller, bracket supporting the motor and a bracket pivoted to the boat and the propeller, shaft between the motor and the propeller, a toothed gear on the motor, a gear on the upper end of the shaft co-acting therewith, a toothed gear on the propeller, a low toothed gear on the lower end of the shaft co-acting therewith, a casing surrounding the lower toothed gear and formed into a sleeve surrounding the lower part of said shaft, a toothed gear fixed to the said sleeve, a toothed gear in mesh with the toothed gear on the sleeve, a casing surrounding said last named toothed gears and the sleeve, and shaft for rotating said toothed gears on the sleeve to effect the turning of the propeller.

6. An appliance for propelling boats comprising a motor, combined with and adapted to drive a propeller, the said appliance being connected to the boat by means of V-shaped bracket and links pivoted to the appliance and to the boat whereby the appliance can be raised and swung over and rest upon a support in the boat.

In witness whereof I have hereunto set my hand in presence of two witnesses.

ERNEST HAMILTON HEINKE.
